UNITED STATES PATENT OFFICE

JULIUS P. COLLVER, OF OLD GREENWICH, CONNECTICUT

TELEPHONE DIAL ACTUATOR

Application filed May 19, 1932. Serial No. 612,279.

This invention relates to telephone dial actuators and has for an object an instrument for effecting rotation of the dial in a simple and efficient manner.

5 An instrument embodying the invention consists of a dial-engaging member carried at the end of a stem having spiral ribs. A manually operable actuator is mounted on the stem and is provided with grooves receiving 10 the ribs, whereby movement of the actuator axially of the stem effects rotation thereof. The dial-engaging member has a finger which is adapted to extend into the finger holes with which the dial is provided. In using this instrument, it is held in the hand and the dial-engaging member is pressed against the dial with the finger inserted in the proper finger hole. Rotation of the stem is effected by 15 movement of the actuator, the extent of rotation of the dial being limited by engagement of the finger with the stop provided for that purpose.

Other objects, novel features and advantages of this invention will be apparent from 20 the following specification and accompanying drawing, wherein:

Fig. 1 is a perspective view of the instrument in position of use;

Fig. 2 shows the instrument in operated 25 position;

Fig. 3 is an axial section partly broken away;

Fig. 4 is a section on the line 4-4 of Fig. 3, and

35 Fig. 5 is an axial section partly broken away of a modified embodiment of the invention.

Referring now more especially to Figs. 1 to 4 inclusive, 10 is a stem provided with spiral 40 ribs 11. In one end of the stem there is pinned a sleeve 12 which is interiorly threaded. A dial-engaging member 13 is provided with a threaded shank 14 by which the dial-engaging member is attached to the stem 10. 45 The dial-engaging member 13 is equipped

with a pad 15 of proper size to be received in the recess provided in the dials of automatic telephones. The member 13 is also provided with a finger 16 which is properly arranged to be received in the finger holes of 50 the telephone dial.

A sleeve 17 is mounted on the stem 10 and is provided with grooves to receive the ribs 11, whereby relative axial movement of the stem and sleeve effects relative rotary movement 55 also. A hollow handle 18 receives the sleeve 17 which is threaded to the handle or otherwise detachably connected thereto. A collar 19 is pinned to the upper end of the stem 11 and a spring 20 is contained within the handle 18 and engages the collar 19 to tend to force the stem out of the handle. 60

In the use of this instrument, the handle 18 is grasped with the hand and the pad 15 arranged in the central recess of the dial 21 of 65 an automatic telephone 22 with the finger 16 extending into the finger hole of the desired number or letter. The handle is then pushed toward the dial, thus rotating the stem 10 and the member 13 until the finger 16 engages the stop 23. The instrument is then lifted and the dial permitted to return to its original position in the usual manner. The spring 20 forces the stem 10 out of the handle 70 18 and the instrument is again ready for use. 75

To facilitate carrying the instrument in the pocket a latch 24 may be provided which will hold the stem against rotation after it has been forced its full length into the handle 18. The overall length of the instrument is 80 thus reduced, making it more compact and more adapted to be carried in the pocket.

In the embodiment of the invention disclosed in Fig. 5, a stem 30 is provided with spiral ribs 31. A sleeve 32 is pinned to the 85 stem 30 and a dial-engaging member 33 is attached to the stem by a shank 34. The dial-engaging member is provided with a pad 35 and a finger 36. A sleeve 37 is mounted on the stem 31 and is provided with 90

grooves receiving the ribs 32, whereby relative axial movement of the stem and the sleeve effect relative rotation thereof. The stem 30 is pinned to a post 38 rotatably mounted in the button 39. A tube 40 is carried by the button 39 and surrounds the stem 30. This stem is provided with a pair of longitudinal slots 41 through which project arms 42 carried by the sleeve 37. A spring 10 43 is interposed between the button and the sleeve 37 and tends to hold the sleeve with the arms 42 in engagement with the lower ends of the slots 41.

In the use of this instrument, the sleeve 37 15 is first pulled toward the button 39 with the latter arranged in the palm of the hand and the first two fingers engaging the arms 42. The spring 43 is compressed and rotation of the stem 30 is effected by the axial movement 20 of the sleeve 37 thereon. The pad 35 is then inserted in the recess in the dial with the finger 36 inserted in the selected finger hole. The arms 42 are then released, thus allowing the spring 43 to move the sleeve 25 axially of the same and effect rotation of the stem to swing the finger 36 into engagement with the stop 23. The instrument is then withdrawn from engagement with the dial and the latter allowed to return to its original 30 position in the normal manner.

It is of course understood that various modifications may be made in the structure above described, without in any way departing from the spirit of the invention as defined 35 in the appended claims.

I claim:

1. A telephone dial-operating instrument comprising a dial-engaging member, a stem connected to said member, a manually operated 40 actuator mounted on said stem, and inter-engaging means on said stem and actuator for effecting rotation of said stem upon movement of the actuator axially of said stem.

45 2. A telephone dial-operating instrument comprising a dial-engaging member, a stem connected to said member, a manually operated actuator mounted on said stem, inter-engaging means on said stem and actuator 50 for effecting rotation of said stem upon movement of the actuator axially of said stem, and resilient means tending to oppose movement of said actuator in one direction.

55 3. A telephone dial-operating instrument comprising a stem provided at one end with a dial-engaging member and a finger adapted to be received in a finger hole of the dial, an operating member mounted on said stem, and inter-engaging means on said stem and 60 operating member for effecting relative rotation upon relative axial movement.

4. A telephone dial-operating instrument comprising a stem provided at one end with a dial-engaging member and a finger adapted 65 to be received in a finger hole of the dial, an

operating member mounted on said stem, inter-engaging means on said stem and operating member for effecting relative rotation upon relative axial movement, and resilient means tending to oppose movement of 70 said operating member in one direction.

5. A telephone dial-operating instrument comprising a hollow handle, a stem carried by said handle, ribs on said stem and grooves in said handle receiving said ribs for effecting rotation of the stem upon movement of the handle axially thereof, and a dial-engaging member carried by said stem, said dial-engaging member having a finger adapted to be inserted in a hole in the dial. 80

6. A telephone dial-operating instrument comprising a hollow handle, a stem carried by said handle, ribs on said stem and grooves in said handle receiving said ribs for effecting rotation of the stem upon movement of the handle axially thereof, a dial-engaging member carried by said stem, said dial-engaging member having a finger adapted to be inserted in a hole in the dial, and resilient means tending to force said stem out of said 90 handle. 85

7. A telephone dial-operating instrument comprising a tube, a stem rotatably mounted within said tube, a sleeve mounted on said stem, spiral ribs on said stem and grooves in 95 said sleeve receiving said ribs for effecting rotation of said stem upon movement of the sleeve axially thereof, a dial-engaging member carried by said stem, said member engaging a finger adapted to be received in a hole 100 in the dial, and operating arms extending from said sleeve through longitudinal slots in said tube.

8. A telephone dial-operating instrument comprising a tube, a stem rotatably mounted within said tube, a sleeve mounted on said stem, spiral ribs on said stem and grooves in 105 said sleeve receiving said ribs for effecting rotation of said stem upon movement of the sleeve axially thereof, a dial-engaging member carried by said stem, said member engaging a finger adapted to be received in a hole 110 in the dial, operating arms extending from said sleeve through longitudinal slots in said tube, and resilient means tending to oppose movement of said sleeve in one direction. 115

In testimony whereof, I have signed my name to this specification.

JULIUS P. COLLVER.
